DON N. THOMPSON, OF SYRACUSE, NEW YORK, ASSIGNOR TO PASS & SEYMOUR INC.,
OF SOLVAY, NEW YORK, A CORPORATION OF NEW YORK.

ELECTRIC-LAMP SOCKET AND SWITCH MECHANISM THEREFOR.

Application filed March 22, 1920. Serial No. 367,856.

This invention has for its object an electric lamp socket and switch construction, which is particularly simple and compact in its organization, economical in manufacture and highly efficient and durable in use. It consists in the novel features and in the combinations and constructions hereinafter set forth and claimed.

In describing this invention, reference is had to the accompanying drawings in which like characters designate corresponding parts in all the views.

Figure 1 is an enlarged vertical sectional view of a lamp socket embodying my invention.

Figure 2 is a sectional view on line 2—2, Fig. 1.

Figure 3 is a vertical sectional view taken partly in elevation, centrally of Fig. 2.

Figure 4 is a sectional view on line 4—4, Fig. 3, looking downwardly, parts being omitted.

Figure 5 is a sectional view on line 5—5, Fig. 3 looking upwardly.

Figure 6 is an inverted plan view of the socket the casing being omitted.

This lamp socket comprises, generally, a skeleton base or frame composed partly of pieces of insulation and partly of metal parts serving to hold the insulating pieces in assembled relation and some serving as conductors, lamp terminals supported by the frame, switch mechanism, and an enclosing casing.

More specifically, the base or frame comprises upper and lower plates as disks 1, 2 of insulation, an upright plate or post 3 of insulation between the disks, additional posts 4, 5 of metal between the disks and serving as wire terminals and having binding devices 6, 7 thereon and an additional post 8 preferably of metal located opposite the post 3 and together therewith supporting the switch mechanism.

The plates or disk may be any suitable tough insulating material as fibre and the post 3 is of the same material, the post 3 being formed with reduced portions or tenons 9, 10 at its ends which fit slots in the disks 1, 2. The metal posts 4, 5 are located diametrically opposite each other and equidistant from the post 3, and are secured to the disks 1, 2, each being here shown as having laterally turned lugs 11, 12 at its upper and lower end respectively, for se-

curement to the disks. As shown the lugs 11 are provided with prongs 13 which pass through holes in the upper disk 1, and which are clinched over on the upper face of the disk. The lugs 12 are formed with threaded holes which receive screws 14 which hold one of the lamp terminals to the base or disk 2 thereof.

15, 16 are the lamp terminals, the terminal 15 being the conventional sleeve of threaded shell and the terminal 16 being located centrally of the sleeve. These terminals may be of any suitable form, size and construction, and are called lamp terminals merely for convenience. They may be, in so far as this invention is concerned, of any suitable arrangement to translate the current to an electrical appliance irrespective of whether said appliance requires a socket or plug or other form of coupling.

The sleeve terminal 15 seats against the outer or lower face of the disk 2 and has a tongue 17 extending through a slot 18, Fig. 4 in the disk and under the foot 12 on the post 4, the companion screw 14 extending through the tongue 17. A disk or washer 19 of insulation is shown as located in the bottom of the shell 15, and the screws 14 extend through this washer and have their heads located in the sleeve where they are accessible through the open end of the sleeve. The screw 14 which threads into the foot 12 for the post 5 extends through a cutout 20 in the sleeve terminal, and hence is insulated from the sleeve terminal.

The central terminal 16 is here shown as in the form of a spring clip at one end of a conductor 22 lying on the lower face of the disk 2 in a diametrical direction and between the disk 2 and washer 19 and has an upturned arm 23 extending through a slot in the disk 2 and terminating in a switch contact 24 on the inner face of the fibre post 3. The conductor is secured to the disk 2 in any suitable manner as by a tubular rivet 25.

26 is a switch contact on the inner face of the post 3 near the disk 1 and connected by a conductor 27 to the post 5. The post 8 is located diametrically opposite the fibre post 3, these two posts supporting the switch mechanism. The post 8 rests at its lower end on the margin of the disk 2 and seats in an indentation therein. It has an arm 28 at its upper end lying on and ex-

tending substantially radially of the lower surface of the upper disk 1. Said arm is secured to the upper disk by prongs 29 extending through holes in the disk 1, and

- 5 clinched over on the upper face thereof and stiffens the frame structure. The switch mechanism comprises a switch arm 31 co-acting with the contacts 24, 26 and means for operating the arm to give it a snap or

10 quick make and break action.

The switch arm 31 is here illustrated as blades extending radially from a body or hub part 32 and having outwardly turned lips 33 on the front and rear sides thereof for guiding the switch blades on to the contacts 24, 26 which overlie and project from the inner face of the post 3 as seen in Fig. 3 providing depressions at 34 between the contacts into which the blades move 15 when out of engagement with the contacts the switch arm being movable axially toward and from the inner face of the post during actuation of said arm.

The means for actuating the switch arm 25 comprises a spindle 35 rotatably mounted in the posts 3 and 8 and a member for transmitting the motion of the spindle to the switch arm. The spindle has a handle 36 at its outer end, the hub of which abuts 30 against the post 8 and an annular shoulder or collar 37 at its inner end which abuts against the outer end face of the fibre post 3, Fig. 3, the handle and collar holding the spindle from substantial endwise movement. The motion transmitting member 38 as here illustrated, is mounted on the spindle and is connected to the switch arm 31 by a lost motion connection which is here shown 35 as provided by a fork or arm 39 projecting from its hub toward the switch arm and between flanges 40 projecting from the hub of the switch arm on opposite sides of the spindle, the fork arms being of comparatively less width than the distance between the flanges to permit the spindle 35 and member 40 to be turned relatively to the switch arm to tension and time the action of the spring to be described which effects the snap action. The member 38 is connected to the spindle 45 35 also by a lost motion connection by radial shoulders 41 struck up from the spindle, these shoulders also holding the member 38 from axial movement outwardly. Said member 38 is also formed with arms 42 extending 50 from its hub or body in the opposite direction from the arms 39 and alternating with said arms. Said arms enclose the shoulders 41 on the spindle and are spaced apart a greater distance than the width of said shoulder whereby there is lost motion 55 between the member 38 and the spindle to permit the snap action as hereinafter described. The member 38 is formed from a sheet metal blank in the form of a maltese cross having a central perforation and hav-

ing diametrically opposite arms bent parallel to each other in one direction and the other arms are bent in the opposite direction.

A coiled spring 43 is inserted between the hub of the part 38 and the switch arm 31 to press the same axially against the contacts 24, 26 and into the depressions 34 between the contacts. The location of this spring and the switch arm at the inside of the fibre post 3 constitutes one feature of this invention. The spring 44 for giving the snap action to the switch member coacts with the member 38 on the arms 42 thereof which in effect constitute a cam and as here shown the spring includes two arms 45 extending on opposite sides of the cam or member 38 and having diverging portions, the inclinations of which meet and form high points or apices 46 coacting with the cam 38 on the arm 42, said spring arms extending crosswise of or at a right angle to the spindle 35. These spring arms are here shown as angular extensions of the bifurcations of the spring 44 which is U shaped and carried by the post 8 and the horizontal extension 28 thereof. The intermediate part 47 of the U extends around the post 8, Figs. 3 and 5, and seats in notches 49 in the post and the bifurcations fulcrum at the ends 90 against the inner sides of lugs 50 depending from the side edges of the horizontal arm or extension of the post 8, said lugs 50 having seats or notches for receiving said bifurcations.

The enclosing casing 51 may be of any suitable form, size and construction, and as it forms no part of this invention, and as the construction thereof is well known any further description is thought to be unnecessary.

In the operation of the switch mechanism (assuming that the switch is "off") upon rotation of the spindle 35 in either direction the cam or member 38 is rotated therewith and spreads the spring arms 45 until the corners or edges of the arms 42 of the cam pass the high points 46 of the spring arms 45 whereupon the spring arms react on the arms 42 of the cam and continue the rotation of the cam relatively to the spindle with a snap action. During such initial rotation of the spindle 38 and the cam, the lost motion between the arms 39 of the cam 38 and the flanges 40 of the switch arm 31 is being taken up and is completely taken up when the spring arms 45 react so that the switch arm is thrown by the reaction of the spring arms 45. The lost motion between the spindle 35 and the cam or member 38 permits the cam to rotate relatively to the spindle during the spreading of the spring arms 45. The operation to throw the switch from "on" to "off" position is the same. The spring 43 yieldingly presses the switch arm

31 against the contacts 24, 26 and insures good electrical connection, and also holds the switch arm in either its "on" or "off" position.

5 This lamp socket, owing to the skeleton construction, of the base and the switch mechanism, is particularly economical of manufacture both as to the base construction itself and as to the assembly of the 10 switch mechanism therein.

What I claim is:

1. A lamp socket comprising a base in the form of a skeleton frame including upper and lower plates of insulation and diametrically disposed posts between the plates, one of said posts being of insulation, lamp terminals supported by the base adjacent the lower plate, switch contacts supported by the base adjacent the post of insulation and 20 electrically connected respectively to the lamp terminals and switch mechanism carried by said posts and including a movable switch arm coacting with said contacts, substantially as and for the purpose specified.

25 2. A lamp socket comprising a skeleton base including upper and lower plates of insulation, and oppositely disposed posts between the plates, one of said posts being of insulation, lamp terminals supported by the base adjacent the lower plate, switch contacts supported by the base adjacent the post of insulation and electrically connected respectively to the lamp terminals, and switch mechanism including a spindle 30 rotatably mounted in the posts and a switch arm operable by the spindle and coacting with the contacts, substantially as and for the purpose set forth.

3. A lamp socket comprising a skeleton 40 plate including upper and lower plates of insulation, a post of insulation between the plates, oppositely disposed metal posts between the plates, and spaced apart from the former post, said posts supporting and holding the plates in spaced apart relation, the metal posts serving as wire terminals, lamp terminals supported by the base adjacent the lower plate, switch contacts associated with the base and mounted on one face of 50 the post of insulation, one contact being connected to one lamp terminal and the other to one of the metal posts, the last mentioned post being electrically connected to the other lamp terminal, and switch mechanism including a spindle journaled at one end in the post of insulation, and a switch arm arranged to coact with said contacts, substantially as and for the purpose set forth.

55 4. A lamp socket comprising a skeleton 60 base including upper and lower plates of insulation, oppositely disposed posts between the plates, one of said posts being of insulation, oppositely disposed metal posts between the plates and spaced apart from the former posts and serving as wire ter-

minals, all of the posts supporting and holding the plates in spaced apart relation, lamp terminals supported by the base adjacent the lower plate, switch contacts located adjacent one of the faces of the post of insulation, one being connected to one lamp terminal and the other to one of said metal posts, the last mentioned post being electrically connected to the other lamp terminal, and switch mechanism including a 70 spindle journaled in the first mentioned posts and including a switch arm arranged to coact with said contacts, substantially as and for the purpose described.

5. A lamp socket comprising a base, switch contacts located in the base and switch mechanism including a rotatable spindle, a switch arm mounted on the spindle and coacting with the contacts, a cam mounted on the spindle and connected to the switch arm by a lost motion connection, the cam being held from substantial axial movement, a compression spring interposed between the cam and the switch arm, and spring means 80 coacting with the cam to effect a snap action of the switch arm through the cam, substantially as and for the purpose described.

6. A lamp socket comprising a base, switch contacts located in the base and switch mechanism including a rotatable 85 spindle, a switch arm mounted on the spindle and connected thereto by a lost motion connection, said cam being provided with bifurcations located on opposite sides of the spindle, and the switch arm being provided with flanges on opposite sides of the bifurcations, the flanges being spaced apart a greater distance than the width of said bifurcations, and spring means coacting with the cam to effect a snap action of the switch 90 arm, substantially as and for the purpose specified.

7. A lamp socket comprising a base, switch contacts located in the base and switch mechanism including a rotatable 100 spindle, a switch arm mounted on the spindle and coacting with the contacts, a cam mounted on the spindle and having two pairs of bifurcations, one pair extending in one direction axially of the spindle, and the other in the opposite direction, and the bifurcations, of one pair alternating with those of the other, the switch arm having means for receiving one pair of bifurcations and the spindle having shoulders between the other pair of bifurcations, and spring means coacting with the latter pair of bifurcations, substantially as and for the 110 purpose set forth.

8. A lamp socket comprising a base, switch contacts located in the base, and switch mechanism including a rotatable spindle, a switch arm mounted on the spindle and movable over the faces of the contacts in a 120 plane at a right angle to the spindle and to

ward the contacts in a direction parallel to the axis of the spindle, a cam mounted on the spindle and held from substantial axial movement, the cam having two active portions, one portion coacting with the switch member to throw the same, and the spindle having means coacting with the cam to transmit rotary motion thereto, spring means coacting with the other portion of the cam to effect a snap action of the cam and the switch member, and a spring interposed between the cam and the switch member to thrust the switch member axially of the shaft toward the switch contacts, substantially as and for the purpose described.

9. A lamp socket comprising a base, switch contacts mounted in the base and switch mechanism in the base including a spindle, switch arms mounted on the spindle and coacting with the contacts, a cam mounted on the spindle and connected thereto by a lost motion connection, spring means for coacting with the cam to impart a snap action to the same, said means comprising a spring 25 U-shaped in general form, the branches thereof having angular extensions arranged crosswise of the spindle and on opposite sides thereof coacting with the cam, the body of the U-shaped formation extending in a general direction parallel to the spindle, substantially as and for the purpose described.

10. A lamp socket comprising a skeleton frame including upper and lower plates of insulation, posts between the plates and holding the same in spaced apart relation, one of the posts having a radially extending arm lying against and secured to the inner face of one of the plates, switch contacts located between the plates and switch mechanism comprising a spindle journaled in two 40 of said posts, a switch arm mounted on the

spindle and coacting with the contacts, means for transmitting the motion of the spindle to the switch arm, and a spring coacting with said means to give the same a snap 45 action, the spring being substantially U-shaped and having angular extensions at the ends of the branches thereof which extensions are arranged on opposite sides of, and coact with, the cam, the body of the U-shaped 50 formation being arranged astride said post and the branches thereof being fulcrumed near their ends, substantially as and for the purpose specified.

11. A lamp socket comprising a skeleton 55 frame including upper and lower plates of insulation, posts between the plates and holding the same in spaced apart relation, switch contacts between the plates and switch mechanism comprising a spindle 60 journaled in two of said posts, a switch arm mounted on the spindle and coacting with the contacts, means for transmitting the motion of the spindle to the switch arm, and a spring coacting with said means to give the 65 same a snap action, the spring being substantially U-shaped and having angular extensions at the ends of the branches thereof which extensions are arranged on opposite sides of, and coact with, the cam, the body of the U-shaped 70 formation being arranged astride one of said posts formed with a diametrical extension and the branches thereof being fulcrumed near their ends against the same, substantially as and for the purpose 75 set forth.

In testimony whereof, I have hereunto signed my name at Syracuse, in the county of Onondaga and State of New York, this 13th day of March, 1920.

DON N. THOMPSON.
